AUTOMATIC PHONOGRAPH

Otto A. Hokanson, Snyder, N. Y., assignor to The Rudolph Wurlitzer Company, North Tonawanda, N. Y., a corporation of Ohio

Application December 21, 1942, Serial No. 469,633

44 Claims. (Cl. 274—10)

1

This invention relates generally to phonographs and more particularly to an automatic phonograph adapted to play records continuously on one or both sides.

One of its objects is to provide a phonograph of this character which is so designed and constructed as to be set at the will of the operator for automatic operation to play a plurality of records in succession on one side only or on both sides, as desired, and after play to discharge the records from the machine, or to be set for manual operation for playing records individually.

Another object of the invention is to provide the phonograph with positive and reliable mechanism for automatically governing the transfer of the records successively from the magazine onto the turntable for play and after play to a point of discharge, as well as for governing the reversal of the records should it be desired to play them on both sides.

Another object is to provide the phonograph with automatically-actuated means for stopping the power unit of the machine when the magazine is emptied of its records and the last played record has been discharged.

A further object of the invention is to provide a continuous playing phonograph of this character which is designed to play 10 or 12 inch diameter records and wherein simple means are provided for manually adjusting the machine for such purpose.

A still further object is to provide a novel arrangement of a record magazine and a tiltable record carrier for loading a record from the magazine onto the carrier and then onto the turntable to play one side of the record, for subsequently reversing the record during a next cycle of movement of the carrier relative to the magazine for playing its opposite side, and after play unloading the record from the turntable and carrier.

The invention has for another object the provision of reliable and efficient means for automatically connecting and disconnecting, at predetermined times, the drive mechanisms associated with the record loading, reversing and unloading operations.

Another object of the invention is to provide a simple and reliable trip mechanism for the tone arm which is operatively included in the circuit of the drive motor and the carrier-governed drive mechanism to either break the motor circuit or render the drive mechanism operative, at the end of play of a record, as determined by the control settings of the phonograph, that is,

2

whether set for manual operation or automatic continuous operation.

Other features of the invention reside in the construction and arrangement of parts herein-after described and particularly pointed out in the appended claims.

In the accompanying drawings:

Figure 1 is a front view of the phonograph embodying my invention. Figure 2 is a top plan view thereof. Figure 3 is an end view of the same looking from the right in Figure 1. Figure 4 is an enlarged fragmentary vertical section taken in the plane of line 4—4, Figure 2. Figure 5 is an enlarged horizontal section taken substantially in the plane of line 5—5, Figure 1. Figure 6 is an enlarged vertical section taken substantially in the plane of line 6—6, Figure 2. Figure 7 is a fragmentary vertical section taken in the plane of line 7—7, Figure 8. Figure 8 is an end view of the trigger mechanism and associated parts. Figures 9 and 10 are enlarged fragmentary views, similar to Figure 7, showing the trigger mechanism in different positions of operation. Figure 11 is a fragmentary view of the cam for initiating the operation of the trigger mechanism. Figure 12 is an enlarged fragmentary face view, partly in section, showing the cam stop and start mechanism. Figure 13 is a fragmentary perspective view of the tone arm trip mechanism and associated parts. Figure 14 is a fragmentary vertical section for the tone arm trip mechanism taken substantially in the plane of line 14—14, Figure 5. Figure 15 is a perspective view of the selective control assembly for adjusting the phonograph to play a record on one or both sides and also for adjusting the setting of the tone arm to play 10" or 12" records. Figure 16 is an enlarged side elevation, partly in section, of the clutch unit associated with the aforesaid control assembly. Figure 17 is a sectional detail view, taken substantially on line 17—17, Figure 15, showing the means for adjusting the setting of the tone arm for playing 10" or 12" records. Figure 18 is a sectional front view of the tone arm support and associated tone arm stop and lift levers. Figure 19 is a detail side view of the magazine switch. Figure 20 is a fragmentary perspective view showing the record-loading actuating means and the trigger for governing the same. Figure 21 is a fragmentary perspective view of the record carrier. Figure 22 is a diagrammatic view of the electric circuit for controlling the various operations of the phonograph.

Referring in detail to the drawings, 20 indi-

cates the base-frame or chassis platform on which the various working parts of the phonograph are mounted, 21 the turntable whose spindle is journaled in a supporting plate 22 suitably spaced from the bottom side of the base frame, 23 the tone arm pivoted at 24 to the top side of said frame adjacent one end thereof to swing laterally to positions for playing either 10" or 12" records, and 25 an electric motor suspended from the plate 22 for operating the turntable as well as the other driving mechanisms of the phonograph. The drive from the motor-shaft 26 to the turntable is through worm gearing 27 to an upright shaft 28 connected by a coupling collar 29 to a second or final drive shaft 30 having a friction drive wheel 31 thereon for releasable engagement with the depending rim or flange of the turntable. A pin 32 on the shaft 30 and a companion helical notch 33 in the coupling collar constitute the driving connection between the two shafts and afford a simple means for automatically bringing the friction wheel into and out of driving engagement with the turntable as the motor is started and stopped. At the opposite end of the base-frame and above the plane of the turntable is a magazine or rack 34 for supporting the records to be played in an edgewise position, the same being substantially chair-shaped and including side arms 35 having forwardly-sloping, record-engaging seats terminating at their free ends in upturned lugs or hooks 36 which retain the lower edges of the records in place thereon and normally prevent their sliding off such arms while the records are inclined side by side in a storage position against the rearwardly sloping back 37 of the magazine.

In its top side between the tone arm and the magazine the base-frame 20 has a well or depression 38 therein in which the turntable 21 is arranged, and surrounding the latter for seating in the outer portion of this well is a record carrier 39 of substantially horseshoe shape which is mounted in a floating-like fashion for elevational adjustment and for a compound tilting movement to swing at predetermined times between the magazine and the turntable for loading or transferring records for playing on one or both sides and at other predetermined times after play to swing in a reverse direction for directing the records by gravity and unloading them through a discharge slot or opening 40 provided in the bottom of the well between the turntable and the magazine, the played records dropping into a suitable cushioned chamber (not shown) provided in the cabinet housing the phonograph mechanism. A guide roller 41 is disposed in operative relation to the discharge slot to facilitate the travel of the played records through the latter. This carrier is provided with a low level seat or ledge 42 for supporting 10" records and a higher level seat or ledge 42^a for supporting 12" records, both seats being disposed concentric with the carrier, whereby the records are centrally supported and retained during the tilting movements of the carrier and brought to an axially-aligned position over the turntable for play in the horizontal position of the carrier. At its open end or that end facing the magazine 34, the carrier has two upright pins or abutments 43 thereon with which the records engage during certain movements of the carrier to and from a record playing position and to a record-discharging position. In the lowered horizontal position of the carrier, which position it assumes during play of a record, its rim 44 about the upper ledge

42^a is substantially flush with the top face of the base frame, and the surface of the turntable 21 is slightly above the level of such ledge so that the records run freely during play.

Mounted on the base-frame for convenient manipulation by the operator are a series of control elements 45, 46, 47 and 48. The control element or lever 45 serves to set the phonograph to play either 10" or 12" records, while the adjoining control element 46 serves to set the phonograph to automatically play one or both sides of each record or to suspend automatic operation, and permit the manual playing of one record at a time without the employment of the loading, reversing or unloading mechanism hereinafter described. The control element or cancelling switch button 47 is disposed in axial relation to the companion lever 46 and functions, when depressed, to stop the playing of a current record and if the machine is set for automatic operation, initiates the change to the next record, or, if the phonograph is set for manual operation, stops it. The control element 48 is in the form of a switch lever and may be opened or closed manually to stop or start the motor 25, although the switch controlled by this lever is adapted to be opened automatically by an electromagnet as will hereinafter appear.

The record carrier 39 is mounted for tilting movement in a vertical plane, first, to swing the left hand or one end thereof from its normal horizontal position about the turntable to an elevation in operative loading relation to the magazine 34; secondly, to swing the closed or opposite end of the carrier upwardly toward the magazine to a position substantially parallel thereto to receive a record therefrom and then downwardly to an inclined position over the turntable; thirdly, to restore the left hand or first-named elevated end of the carrier to its initial position to deposit the record on the turntable for play; fourthly, after play, and assuming the same record is to be played on the opposite side, to elevate and swing the carrier to the positions previously described, and, when in a position tilted beyond the vertical, cause the record thereon to be tilted outwardly so that its upper edge falls by gravity against the face of the foremost record on the magazine or against the rear wall thereof if the magazine is emptied of records, and as the carrier is again lowered the record is caused to slide on such upper edge and gravitate down the face of such record on the magazine while its opposite or lower edge slides and gravitates down the companion carrier-seat 42 or 42^a to cause a reversal of position of the record for playing its opposite side; and, fifthly, after play, that end of the carrier adjacent the magazine is lowered to lift the record from the turntable and it subsequently slides by gravity toward and is directed through the discharge opening 40 in the base-frame 20 and over the guide roller 41, the latter elevating the record over the abutments 43 in the manner shown by dotted lines in Figure 4. Following this cycle, the operation of the phonograph continues automatically until all of the records placed in the magazine have been played, when it stops. The mechanism for controlling the tilting of the carrier to accomplish this record loading and unloading cycle of operations is preferably constructed as follows:

Connected by worm gearing 49 to the motor-shaft 26 is a driven shaft 50 having a gear 51 fixed thereon meshing with an idler gear 52 on a shaft 53, the latter gear meshing with a gear

54 fixed on a cam shaft 55 which only turns during the record-changing cycles and is at rest during play of a record. These shafts are disposed transversely of the base-frame and are journaled in suitable bearings provided in brackets 56 depending from such frame. Fixed on the cam shaft 55 are two channel cams 57 and 58 which may be made integrally with the channels in the opposite faces thereof, and which govern the tilting movements of the carrier 39 in proper sequence. The cam 57 constitutes the record-loading or reversing cam for actuating the carrier through its greatest degree of swinging movement toward and from the magazine 34, while the companion cam 58 constitutes the record-lift cam for actuating the carrier to an elevation to bring one end thereof to and from its loading position in operative relation to the magazine as well as to swing it to and from its record-discharging or unloading position. Fixed on the rear end of a rock shaft 59 disposed parallel to the cam shaft is a rock arm 60 having a follower 61 engaging the rearwardly-facing groove or channel in the cam 58 and at the front end of such rock shaft is a lift arm 62 connected by a link 63 with the lower end of a vertical slide 64 mounted on a roller-bearing guide 65 applied to a bracket 66 suspended from the plate 22. Pivotally connected at 67 to the upper end of this slide is that end of the carrier adjoining the magazine, so that at predetermined times in the movement of the cam 58 the open end of the carrier is lifted to and from an elevation in record-loading relation to the magazine side arms or lowered to and from a reversely-inclined position to discharge a played record from the carrier.

Cooperating with the cam 57 is a pendant rock arm 68 having a follower 69 engaging the forwardly-facing groove in such cam and connected at its lower end by a link 70 to one of two rock levers 71, 72 fixed on a rock shaft 73, the other rock lever being connected by a link 74 to the carrier at a point spaced inwardly from the connection of the slide 64 thereto, the pivot 67 of the latter constituting a fulcrum about which the carrier is tilted to and from its loading or record-reversing position in response to the predetermined movements of the cam 57 and interposed connections.

The initial upward movement of the carrier 39 by the respective cams 57, 58 and their actuated connections takes place substantially simultaneously, but when the open end of the carrier opposite the magazine reaches an elevation approximating the record-supporting seats 35 thereof, such end of the carrier remains in that position while its opposite end continues to rise and is tilted to a position slightly beyond the vertical, say about three degrees, after which it returns to a position about fifteen degrees from the vertical, in which position the carrier is adapted to receive a record from the magazine, it being understood that only one record at a time is transferred and that the phonograph can be set to cause the automatic playing of one or both sides of a record. A record is loaded or transferred to the carrier when the latter is in the last-named tilted position by shifting the foremost record in the magazine over the retaining lugs 36 of the magazine-seats and allowing it to drop by gravity in edgewise engagement with the then adjoining-positioned carrier-pins 43, so that when the carrier is lowered the record contacts at one edge with the foremost record in

the magazine and at its diametrically opposite lower edge with the companion seat 42 or 42^a of the carrier, being gradually lowered and caused to gravitate into its properly centered position on the carrier for deposit onto the turntable 21. The means for thus transferring or loading a record onto the carrier is preferably constructed as follows:

Formed in the lower portion of the magazine inwardly of each side arm 35 is a vertical slot 75 in which is arranged a vertically-swinging, record-loading or ejector arm 76, both arms 76 being pivoted at 77 on the magazine and connected by a common link 78 with one arm of a bell crank lever 79 fixed on a rock shaft 80 journaled on the underside of the base-frame 20. The other arm of this lever is connected by a link 81 to a companion lever 82 fixed on a rock shaft 83 disposed parallel to the cam shaft 55. Also fixed to this rock shaft is an arm 84 to which is pivoted, intermediate its ends, a laterally movable cam follower 85 adapted for movement into and out of the path of a trip or sub-cam 86 applied to the face of one of the carrier-actuating cams, say the cam 58. When presented to the trip cam, the follower 85 is rocked by the latter in a direction to swing the record-loading arms 76 from their normal lowered or inactive position to a position in which their curved and pointed free ends engage between the lower marginal rear side of the foremost record in the magazine to be transferred and the opposing front side of the next adjoining record to thereby displace such foremost record over the seat-lugs 36 and onto the supporting pins 43 of the carrier, the curved front edges of the arms 76 acting as cams in so displacing the record with the top edge of the latter resting against the upper face of the adjoining record in the magazine.

In transferring a record from the magazine onto the carrier 39, the latter assumes the position shown by full lines in Figure 6, with the displaced record supported in the manner just stated. The carrier then swings downwardly, causing the record to gravitate with its front side facing upward and then slide down the carrier to an axial position over the turntable, being governed by one or the other of the carrier seats 42 or 42^a, after which the carrier is tilted from its dot-dash line position to its dotted line position shown in Figure 6 for depositing the record on the turntable. For reversing that record for play, the carrier is swung upwardly beyond its full line position in Figure 6 to the dotted line position shown in Figure 1, to first tip the record from the carrier against the magazine. Then, upon lowering the carrier, the unplayed side of the record is gravitated face up to its play position over the turntable. In repeating a record on the same side, the carrier cycle is to the inclined position shown in Figure 6, being not beyond the vertical which is the cycle necessary to reverse the record.

A spring 87 is connected to the outer end of the cam follower 85 to normally urge it to an inoperative position clear of the path of the trip cam 86, so as to prevent the actuation of such follower and its associated parts to a record-unloading position. Movement of this follower to its operative position is accomplished by a shiftable trigger element 88 disposed for contacting engagement at its upper end with a laterally-deflected cam portion 89 formed at the outer end of the cam follower, so that when the trigger element is shifted in a direction lengthwise of the

follower and toward the rock shaft 83, it causes the lateral displacement of the follower into the path of said cam 86. Shifting of the trigger element in the opposite direction causes the spring 87 to urge the follower 85 to its inoperative position. This trigger element also functions to govern the unloading movement of the carrier to discharge a record after play.

The means for controlling the movement of the trigger element 88 to automatically suspend the loading and unloading operations, when a record is to be reversed to play both sides, is preferably constructed as follows:

The actuation of this trigger at predetermined times, depending on the setting of the manual control element 46, is initiated from the lift cam 52 whose follower-engaging channel 58^a has a branch or auxiliary outer portion 58^b adapted to be opened or closed to travel by the follower 60, 61 of the carrier lift assembly 62-67, inclusive, through the medium of an oscillating gate or switch-like member 90 pivoted at 91 to the face of the lift cam and having an actuating lever 92 connected thereto including a tappet finger 93 projecting from the periphery of such cam. A spring 94 connected to the lever 92 normally urges the gate to a position to establish communication between the main and auxiliary channel portions of the cam, as shown in Figure 10, and direct the follower 61 into such auxiliary channel portion, resulting in the lowering of that end of the carrier 39 adjacent the magazine 34 below its normal horizontal position to unload the played record by causing it to be discharged through the frame-opening 40. In the other position of the switching gate 90, it extends across the mouth of the auxiliary channel portion 58^b of the cam and compels the follower 60, 61 to follow the adjoining portion of the main cam channel 58^a so as not to affect the normal horizontal position of the carrier at this stage of movement of the cam.

The trigger element 88 is disposed at one side of the cam 57, 58 and is pivoted at its lower end at 95 to swing in a vertical plane, and coupled thereto by a pin and slot connection 96 for actuation thereby is a pivoted gate-controlling cam 97 which is adapted to be shifted, when the trigger is rocked in one direction or the other, into and out of the operating path of the gate lever finger 93 to in turn actuate the gate 90 to a position to close the mouth of the cam-channel 58^b. The rocking of the trigger to and from its gate-tripping position is effected by a lifter bar 98 having a stud 99 at its upper end engageable with one or the other of a pair of notches 100 formed in the lower end of the trigger 88 at either side of its pivot. The lower end of this lifter bar is pivotally connected to a vertically-swinging lifter lever 101 whose free end is disposed in the operating path of a sub or trip cam 102 applied to the face of the left cam 57, so that when such trip cam encounters the lifter lever it elevates the lift bar to cause its stud 99 to rock the trigger to the right or to the left depending on the notch engaged at the time. A spring 103 connected to the lifter bar tends to return it and the lifter lever to initial position after actuation by the cam. An over-center spring 104 is provided for holding the trigger in each of its alternate positions, this spring being attached at its upper end to a stud 105 fixed on the free end of a locking rock arm 106 pivoted alongside the upper end of the trigger and engaging a longitudinal slot 107 in the latter. This stud constitutes that portion of the trigger which

is adapted to abut at its rear end against the deflected cam portion 84 of the follower 85 and, in response to the oscillation of the trigger in one direction or the other, to govern the shifting of such follower into and out of the path of the trip cam 86. By this trigger-actuating mechanism, it will be seen that at one revolution of the cam 57, 58 the gate-controlling cam 97 is presented into the path of the tappet finger 93 of the gate-actuating lever 92 to move the gate 90 to a position to close the mouth of the outer cam channel 58^b to thereby prevent the actuation of the unloading mechanism to discharge the played record and instead cause the record to remain on the carrier 39 and be inverted to play the opposite side. On the succeeding revolution of the cam 57, 58, after the record has been played on its opposite side, the trigger is rocked in the opposite direction to remove the gate cam from the path of the gate lever finger, thereby allowing the spring 94 to maintain the gate in its normal position in which the record-unloading cam channel 58^a is in open communication with the main cam channel 58^b to cause the actuation of the lift rock arm 62 in a direction to lower the lift end of the carrier 39 to discharge the record therefrom.

Means are also provided in operative relation to the trigger-actuating mechanism for suppressing its automatic, alternating action and completely rendering such mechanism inoperative when it is desired to either play each record in the magazine on one side only, or to operate the phonograph manually and not continuously, as determined by the setting of the hand lever 46. For this purpose, a suppressing member or lever 108 is provided which is pivoted on the trigger-pivot 95 for manual movement to and from an operative position and has a stud 109 at its upper end which is adapted to abut the trigger 88 for moving the latter into a position to swing the gate-cam 97 out of the path of the gate lever finger 93, thus keeping the gate 90 in its normal record-unloading position shown in Figure 10. The lower end of the suppressor lever 108 is so shaped as to make contact along its edge 110 with the notch-engaging stud 99 of the lifter bar 98 and so displace the latter that its stud is free and clear of the trigger-notches 100. Thus, at each contact of the trip cam 102 with the lifter lever 101, the lifter bar stud 99 moves ineffectually past the trigger-notches and along the bridging edge 110 of the suppressor lever. The spring 104 is connected at its lower end to this suppressor lever, and in addition to its trigger-holding function, also acts to urge the suppressor lever into its operative position shown in Figure 10.

The manual actuation of the suppressor lever 108 is controlled from the hand lever 46 which is fixed on the upper end of an upright shaft 111 suitably supported in the base frame 20 and provided at its lower end with an arm or detent plate 112 connected by a link 113 with a similar arm 114 fixed on a horizontal control shaft 115 extending transversely of the phonograph. Also fixed on this control shaft is a crank arm 116 having a lost motion or pin and slot connection 117 with a link 118 joined at its other end to the suppressor lever above the pivot thereof. Thus, when the hand lever is moved to a position to turn the control shaft clockwise, with the pin and slot connection 117 abutting, the suppressor is moved to its inoperative position shown in Figure 9 so as not to interfere with the automatic playing of the records on both sides. When the hand lever is moved to its other position and

the control shaft turned counterclockwise, the pin moves away from the slot of the connection 117, and the spring 104 causes the suppressor to be automatically shifted to its operative position and set the phonograph for playing the records on one side only. In this last-named position of the parts, it will be noted that the pin and slot connection 117 is such that a further independent counter-clockwise movement of the control shaft 115 is permitted, without disturbing the setting of the suppressor, for the purpose of initiating the operation of other parts hereinafter described for playing records singly.

The detent plate 112, which is actuated by the hand lever 46, is provided in one edge with a row of notches 119 with one or another of which a spring-pressed detent 120 is engageable for retaining the parts associated therewith in a set position. The underside of this plate has a cam 121 thereon made of insulating material which is adapted to engage the common movable blade 122 of two switches 123, 124 and by so doing opening one and closing the other and vice versa. When the hand lever 46 is set for automatic operation to play one or two sides of the records, the switch blade 122 is simultaneously engaged with the switch 123 to govern a solenoid circuit hereinafter described, and when said lever is set for manual playing of the records such switch blade is moved to a position to open the solenoid circuit and be closed across the switch 124 to control automatically the electromagnetic opening of the motor switch operationally associated with the hand lever 48.

The mechanism for automatically raising, lowering and swinging the tone arm is preferably constructed as follows:

Applied to the tone arm spindle 125 is a lift rod 126 which rests at its lower end on a horizontally-swinging lift lever 127 pivoted intermediate its ends at 128 on a suitable bracket depending from the frame 20 and having an inclined cam-like portion 129 thereon at one side of its pivot with which the lift rod is adapted to engage for governing the raising and lowering movements of the tone arm. At the opposite side of its pivot this lift lever is connected by a link 130 with the arm 131 of a clutch 132 mounted for axial movement on a tone arm actuating rock shaft 133 disposed parallel to the control shaft 115. Disposed in parallel relation with and beneath the lift lever, and also pivoted at 128, is a stop lever 134, said levers having opposing adjusting screws 135 mounted thereon adjacent their free ends and between which a tone arm trip 136, radiating from the spindle, extends. By adjusting the screws, the tone arm and its trip can be properly set as desired. At its opposite free end the stop lever is provided with a stop lug or abutment 137, and each lever 127, 134 has a lug 138 bent upwardly therefrom at their opposite edges and to which the ends of a spring 139 are connected. This spring constantly urges the lift lever 127 to abut at its side edge against the opposing abutment 138 on the stop lever 134 to be thereby held in an operative position beneath the lift rod 126.

The tone arm actuating rock shaft 133 has motion transmitted to it from a follower arm 140 mounted thereon and engaging a cam 141 applied to the cam shaft 55, and the clutch 132 is shiftable to a driving or released position to govern the movement of the tone arm. As shown in Figure 15, this clutch has a substantially Y-shaped notch 142, in one or both diametrically

opposite sides and engaging the same is a pin 143 applied to the rock shaft. The clutch is adapted to be shifted in one direction axially of the shaft 133 to bring the narrow end of its notch into driving engagement with the shaft-pin to transmit the cam-actuated motion of the shaft to the clutch, or in the opposite direction to a released position by bringing the flaring end of its notch in register with the shaft-pin, in which position the angular distance between the flared edges of the clutch notch is too great to bring the shaft-pin in engagement therewith and no motion of the rock shaft is transmitted to the clutch and tone arm connections by the cam 141 and its follower. The shifting of the clutch is controlled by a vertically-swinging lever 144 pivoted intermediate its ends at 145 and provided at its lower end with a fork engaging an annular groove in the clutch, while its upper end terminates in a flange 146 having a diagonally-extending slot 147 therein. Extending into this slot for shifting the clutch lever to its engaged and released positions is a coupling member 148 fixed on the control shaft 115. By this construction, when the hand lever 46 is set for automatic operation to play one or both sides of the records, the control shaft is accordingly turned in a direction to cause its coupling member 148 to shift the clutch lever 144 to its engaged position, so that at a predetermined time in the playing cycle the cam 141 will rock the tone arm shaft 133 and arm 131 and other parts connected to the tone arm in a direction to swing the latter back after play. When the hand lever 46 is set for manual play, the clutch is shifted to a released position with the flaring portion of its notch 142 in the plane of the shaft-pin 143, whereby the tone arm is disconnected from the actuating cam and is free to be swung in and out by hand.

Disposed for operative engagement with and in the moving path of the lug 137 of the tone arm stop lever 134 is an adjustable means for predetermining the setting of the tone arm for playing 45 10" or 12" records, such means being manually governed by the control lever 45. The latter is attached at its upper end to an upright shaft 149 suitably supported in the frame 20 and provided at its lower end with an arm or detent plate 150 having notches 151 at one edge thereof for engagement by a spring-pressed detent 152 for retaining the parts in a set position of adjustment. This detent plate has a curved slot 153 therein engaged by a follower pin 154 fixed on the front 50 end of a horizontal control shaft 155 also journaled in the frame and provided adjacent its rear end with an arm or plate 156 having horizontally spaced adjusting screws 157 and 158 applied thereto which are adapted to be set so their shanks extend different distances from the rear face of said plate for abutting engagement by the stop lever lug 137 to thereby predetermine the position of the lift and stop levers 127, 134 for playing a 10" or a 12" record. By turning the 55 hand lever 45 to its 10" or 12" record play position, the shaft 155 is accordingly turned in one direction or the other through the operative connection 153, 154 to present the screw 157 or 158 into the path of travel of the stop lever lug 137 to thereby set the tone arm in position for playing the size of records placed in the magazine. When the clutch 132 is in its engaged position and the cam shaft 55 set in motion, at the start of the playing cycle, the clutch-arm 131 is turned 60 70 to shift the link 130 in a direction to jointly turn

the tone arm lift lever 123 and the stop lever 134, through the medium of the connecting spring 139 and stop-lever lug 138, to the active position shown in Figure 15, until the lug 137 on the stop lever abuts the 10" or 12" screw 151 or 158 then in its path, at which time the stop lever is arrested in its movement and for the remainder of the operating clutching stroke the lift lever continues to turn with the result that the coupling or lift lever return spring 139 is placed under tension, the screw 135 on the lift lever is drawn away from the trip arm 136, and the inclined cam portion 129 of the lift lever is simultaneously withdrawn from beneath the tone arm lift rod 126 to permit the tone arm to drop onto the starting groove of the record for play. The pre-adjustment of the stop lever screws 135 and the record-gaging screws 151, 158 place the trip arm 136 in a definite predetermined starting position to properly locate the tone arm for playing the companion sized record and with the needle in register with the starting groove of the record. When the tone arm is thus properly set for play, the cam shaft 55 is stopped and the playing of the record is started. The lift lever adjusting screw 135, when such lever is in play-starting position, is at such a distance from the initial position of the trip arm 136 that the latter, in its final position, can never contact the screw, so that such trip arm moves with the tone arm without hindrance until the latter reaches the inner or tripping groove of the record.

The tone arm trip mechanism, initiated by the trip arm 136 when the playing of the record is completed and the eccentric or terminal groove encountered by the needle, is preferably constructed as follows:

Applied to the free end of the trip arm for limited pivotal movement in a vertical plane is a trip dog or pawl 159 which is adapted at its sharpened lower edge to ride over an arcuate ratchet bar 160 having ratchet teeth 161 thereon over the outer part of the dog's travel. The inner or toothless part of this bar serves to keep the dog always above the ratchet teeth so that there is no possibility of premature tripping. The ratchet bar has a supporting arm 162 projecting outwardly therefrom which is pivoted for horizontally-swinging movement on a pivot 163 applied to the adjoining end of a vertically-swinging, switch-tripping rock lever 164 pivoted at 165 to one of the shaft-brackets or other part of the frame of the machine. The other end of this rock lever bears on a four-pointed cam 166 fixed on the idler shaft 53 and has a spring 167 connected thereto for urging it toward facial contact with such cam. Mounted on the lever 164 is a normally open trip switch 168 included in the circuit of a solenoid 169 and adapted to be moved to a closed position by an insulating block 170 applied to the outer end of the bracket supporting arm 162 when the ratchet bar 160 is rocked laterally by the trip dog 159 at the end of play of a record. The ratchet arm is normally held in a switch-opened position by a spring 171 coiled about the pivot 163 and bearing against one side of such arm, while the opposite side of the latter abuts against an adjusting screw 172 mounted on a lateral extension of the lever 164. By this construction, as the tone arm swings inwardly during the playing of the record, the dog 159 is advanced along the ratchet bar 160 and the trip cam 166 causes the trip switch lever 164 to oscillate and the ratchet bar to move up and down beneath the dog at a comparatively rapid rate relative to the

slower inward swing of the tone arm. When the dog reaches the toothed portion 161 of the ratchet arm while the record is still playing, such teeth are forced downwardly by the cam 166 before the dog can advance, while in contact with a tooth, a sufficient distance to effect the closing of the switch 168. However, when the tone arm reaches the eccentric groove in the record, the dog, when engaged with a ratchet tooth, is suddenly advanced a considerable distance to accordingly impart a sufficient lateral movement to the arm 162, before the next downward movement is imparted to it by the cam, to close the switch and energize the solenoid 169 included in the circuit thereof, should the machine be set for automatic play.

During the playing of the phonograph, the idler shaft 53 is continuously rotated by the gears 51, 52 to render the trip cam 166 operative, while the cam shaft 55, which governs the record loading and unloading mechanism as well as the movement of the tone arm to its return and starting positions, is stopped and its driven gear 54 released from driving engagement with the idler gear 52 until the solenoid 169 is energized by the closing of the trip switch 168 when the hand lever 46 is set in its automatic play position with the solenoid switch 122, 123 closed. For this purpose, the cam shaft gear 54 is preferably of the mutilated type having an untoothed segment 173 which clears the idler gear during stoppage of the cam shaft, and at one end of such segment is a spring-pressed tooth 174 to insure proper meshing of the idler gear and cam shaft gear when the starting operation is initiated. Projecting from one side of the gear 54 is a roller 175 with which a vertically-swinging, hook-ended stop lever 176 is engageable for arresting the movement of this gear when its untoothed segment is opposite the idler gear. Mounted on the same pivot 177 on which the stop lever is fulcrumed is a cam-like lever 178 which is adapted to be lifted by the roller, at a predetermined time in the rotation of the cam shaft and as such roller approaches the hooked end of the lever 176, so that when the roller engages the hook of the latter, the outer edge of the cam lever engages the opposite side of the roller and is held in contact therewith and against inward displacement therefrom until the hooked lever is released. Connected to this cam lever is a comparatively strong spring 179 which is under tension or in an energy storing position when such lever is raised or in contacting relation with the roller, and which, upon release of the stop lever from the roller, expends its energy by a wedging action on such roller to initiate the starting of the cam shaft sufficiently to bring its gear 54 into mesh with the idler gear 52. A spring 180 connected to the stop lever normally urges it in a direction to hook about the roller 175, and in this connection companion stops 181 and 182 are provided for limiting the downward movement of this lever. Operatively connected to the hooked end of the stop lever 176 is a link-joined plunger 183 of the solenoid 169, so that when the circuit of the latter is closed by the trip switch 168 when the manually-set switch 122, 123 is in its closed position for automatic play, the solenoid-plunger is shifted in a direction to release the lever from the roller 175 and cause the spring 179 to expend its energy and in so doing rock the cam lever against such roller to in turn start the rotation of the gear 54 and bring its spring-pressed tooth 174 into driving engagement with the idler gear 52. An adjustable cushioned stop 184 of any well known

type is disposed in the path of the stop lever for preventing clashing of the solenoid-plunger and such lever at the end of the releasing stroke.

The electric circuit for controlling the phonograph is diagrammatically shown in Fig. 22, wherein the wires 185, 186 indicate the power line to which the leads 187 and 188 of the motor 25 are connected. Included in this motor circuit is a switch 189 which is of the type to be manually opened and closed by the hand lever 48 and which is adapted to be automatically opened under certain conditions by an electromagnet 190 when the same is energized. One end of the coil of this electromagnet is connected to the wire 188, while its other end is connected by a wire 191 to the switch terminal 124 associated with the common switch blade 122, the latter being governed by the hand lever 46. The companion switch terminal 123 associated with the common switch blade 122 is connected by a wire 192 with one end of the coil of the solenoid 169, while the other end of such coil is connected by a wire 193 with the power wire 186. The common switch blade 122, which is adapted to be moved by the hand lever 46 into contact to close the switch 123 or 124, is connected by a wire 194 with one of the terminals of the tone arm trip 168, the other terminal of such switch being connected by a wire 195 to the power wire 185. Shunted in the circuit of this trip switch is a normally open cancelling switch 196 adapted to be manually closed by the switch button 47. For manual or automatic operation of the phonograph, the switch 189 is manually closed and can be opened manually or automatically when the electromagnet 190 is energized. When the control lever 46 is set in position for manual operation, it opens the solenoid-governing switch terminal 123 and the switch blade 122 is closed across the companion terminal 124 leading to the electromagnet 190, so that when the tone arm trip switch 168 is closed, the electromagnet is energized and the motor switch is automatically opened to stop the phonograph. When the lever 46 is set for automatic operation, the position of the switches controlled thereby is reversed with the switch terminal 124 being opened and the terminal 123 being closed, so that when the tone arm trip switch is closed under these conditions the motor continues to operate and the solenoid 169 is energized to release the stop lever 176 from the roller 175 on the cam shaft gear 54 and bring the latter into driving engagement with the idler gear 52 to render operative the loading and unloading or reversing mechanism of the carrier 39, accordingly as the phonograph is set to play one or both sides of the record. The cancelling switch 196 is movable to a closed position manually by pressing the button 47, and serves during manual operation of the phonograph to stop it by closing the circuit including the electromagnet 190 to automatically open the motor switch 189, and during automatic control of the phonograph to close the circuit of the solenoid 169 to thereby stop the playing of the record then on the turntable and cause the cam shaft 55 to be rotated to return the tone arm to its initial position and, depending on the control setting, unloading that record or reversing it for play on its opposite side.

Also included in the motor circuit is a magazine-governing switch 197 which is adapted to be closed when the last record in the magazine-rack 34 is removed for play, and in series with this switch is a normally open, slide-actuated final stop switch 198 governed by one of the vertically-

movable, carrier-actuating slides 64 and adapted to be closed when the slides return to a normal position after unloading the last record from the carrier 39, when the phonograph is free of records at the end of automatic play. The switch 197 is connected at one terminal by a wire 199 to the motor lead 187 while the other terminal thereof is connected to one of the terminals of the switch 198, the companion terminal of the latter being connected by a wire 200 with the wire 191 leading to the switch-opening electromagnet 190, so that when both of these switches are closed, the electromagnet is energized and the motor switch 189 is opened.

By preference, the magazine switch is actuated by a vertically-swinging lever 201 operating in a slot 202 of the base portion of the magazine 34 between the carrier-loading arms 76 and in contacting relation at its upper edge with the records therein which act to depress the lever to a switch-opening position. A spring 203 connected to this lever tends to raise it to a switch-closing position. The slide-actuated stop switch 198 is preferably moved to a closed position by a rock cam 204 disposed in the path of the upward travel of a one-way operable trip element 205 mounted at the lower end of the companion slide 64, so that when the carrier 39 returns to normal, after having unloaded the last record, the cam is rocked in a direction to close the switch. On the down-stroke of the slide, the element 205 merely rides over the cam without affecting the switch.

When the phonograph is set for manual play by setting the control lever 46 in such position, the tone arm controlling clutch 132 is released to permit the tone arm to be freely shifted manually to and from a playing position, and in conjunction with this setting a means is also brought into operation for preventing the tone arm stop lever 134 from contacting the 10" and 12" record-adjusting screws 157, 158. For this purpose, a stop or intercepting arm 206 is loosely mounted on the inner end of the size-setting control shaft 155 which is adapted to be projected to a position adjacent and across the ends of the screws 157 and 158 to prevent the stop lever lug 137 abutting the latter during manual play and which is adapted to be normally urged to a position at one side of such screws during automatic play, so as not to interfere with the automatic setting of the tone arm for playing 10" or 12" records. This stop arm 206 is operatively connected to the manually-controlled rock shaft 115 through the medium of a crank arm 207 fixed on such shaft and connected by a link 208 with a second arm 209 connected integrally with the stop arm. The crank arm 207 has a slot 210 therein through which the companion end of the link 208 extends, and a spring 211 connected to the latter normally urges it against one end of the link-slot and the stop arm to its released position clear of the adjusting screws 157, 158. By this construction, when the control lever 46 is moved to its manual play position, the rock shaft 115 is moved in a counter-clockwise direction to pull the stop arm 206 into a position opposite the ends of the 10" and 12" record adjusting screws. On the other hand, when this control lever is moved to its "1" and "2" positions for setting the phonograph to automatically play the records on one or two sides, the rock shaft is moved in a clockwise direction which causes the spring 211 to shift the link 208 relative to the arm-slot 210 in a direction to rock the stop arm clear of the ends of the record-adjusting screws. Simultaneously with these re-

spective settings of the control lever 46, the clutch 132 is accordingly released or engaged, and the suppressor lever 108 is likewise shifted, through its connections 116, 117 and 118 to the rock shaft 115, to a position for suppressing automatic operation of the record-transferring mechanism during manual play and to a position for rendering such mechanism operative during automatic play of the records on one or both sides.

When the phonograph is set for manual play, the tone arm lift and stop levers 127 and 134 are inactive because of the released position of the clutch 132, and a spring 212 is connected to the thrust link 138 to urge and maintain the lift lever in its retracted position, such spring being stronger than the spring 139 connecting said levers.

I claim as my invention:

1. In an automatic phonograph, the combination of a turntable, means fixed at one side of the turntable for supporting records in a substantially upright position, means supported for vertically-swinging movement between said turntable and said record-supporting means for transferring a record from the latter onto the turntable, said transfer means having elements thereon for supporting a record in edgewise relation thereto during the initial portion of its swinging movement to a position over the turntable and other means for slidably supporting the marginal sides of the record during the remaining portion of its swinging movement for guiding the record to and centering it over the turntable, and means operatively connected to said transfer means for actuating it.

2. In an automatic phonograph, the combination of a turntable, means fixed at one side of the turntable for supporting records in a substantially upright position above the plane thereof, vertically-displaceable means normally supported about the turntable for movement to and from the record-supporting means to receive a record therefrom and transfer it onto the turntable, and means operatively connected to said vertically-displaceable means for actuating it at predetermined times to and from an elevation in operative record-transferring relation to said supporting means and in a swinging path toward and from such record-supporting means, whereby during the transfer of a record for play it is slidably guided on said displaceable means toward and deposited on the turntable.

3. In an automatic phonograph, the combination of a turntable, a magazine at one side thereof for supporting a plurality of records side by side in a substantially upright position, a carrier mounted for swinging movement between the turntable and the magazine for receiving and transferring a record from said magazine by gravity to a deposited playing position onto the turntable while sustained in a bridging fashion between the adjoining record in the magazine and the descending carrier, means operatively connected to said carrier for actuating it to its record-receiving and record-depositing position, and shiftable means applied to the magazine and engageable with the bottom of the foremost record therein for displacing it from its supporting position on the latter to a like supporting position on the carrier when the same is in its raised, record-receiving position.

4. In an automatic phonograph, the combination of a turntable, a magazine at one side thereof for supporting a plurality of records thereon, a vertically-displaceable member at one side of the

turntable and below the magazine, a carrier mounted on said member for swinging movement between the turntable and the magazine to transfer a record from the latter to the former and also movable in a reversely-swinging direction to a position inclined to the turntable to discharge a played record therefrom by gravity, and means operatively connected to said displaceable member and said carrier for actuating such parts at predetermined times to their record-transferring position and to their record-discharging position.

5. In an automatic phonograph, the combination of a turntable, a magazine at one side thereof having seats for supporting a plurality of records side by side in a substantially upright position, means on said magazine in operative relation to said seats and releasably engageable with the foremost record thereon for displacing its lower edge from supporting engagement with the magazine-seats, and a vertically-swinging carrier pivoted at one end adjacent the magazine and movable between the turntable and the magazine to transfer a record from the latter onto the former, the pivoted end of the carrier having record-engaging abutments thereon adapted to be positioned in operative relation to the magazine in the raised position of the carrier to receive a record dislodged from the magazine-seats by said displacing means.

6. In an automatic phonograph, the combination of a turntable, a magazine at one side thereof for supporting a plurality of records side by side in a substantially upright position for transfer onto the turntable to play one or both sides thereof, a compound tilting carrier normally disposed about the turntable during play and movable between the turntable and the magazine to transfer, at predetermined times, a record for play on one side and after play, jointly with said magazine, governing the reverse positioning of the record to play its opposite side, the record during its initial transfer as well as its reversal movements being sustained at its edges between the magazine and the carrier and free to slide by gravity while so supported during the descending movement of the carrier to its record-depositing position over the turntable, and means for actuating said carrier at predetermined times in one or another of its compound movements to cause the record to be played on one side or the other.

7. In an automatic phonograph, a turntable, a record magazine at one side thereof, a combined vertically-displaceable and tilttable carrier movable relatively to such parts for loading a record from the magazine onto the turntable for play on one side when such carrier is displaced in one direction, for causing the reversal of the record for play on its opposite side when the carrier is displaced in the opposite direction, and to a position tilted relatively to the turntable to unload a played record therefrom, and means operatively connected to said carrier to actuate it toward and from the magazine to successively transfer a record for play on one side and then cause its reversal for play on its opposite side, and to subsequently actuate it to and from an unloading tilted position relative to the turntable to cause the record to gravitate therefrom.

8. In an automatic phonograph, the combination of a turntable, a magazine at one side thereof for supporting a plurality of records thereon, a vertically-displaceable fulcrum-bearing member at one side of the turntable and movable to different elevations, a carrier mounted on said mem-

ber for compound swinging movement, in one of the elevated positions of such member, between the turntable and the magazine to transfer a record from the latter to the former and after play to reverse the record for play on its opposite side, said carrier being movable in a reversed direction in the other elevated position of said member to a position inclined to the turntable to discharge a played record therefrom by gravity, shiftable means applied to the magazine and engageable with the bottom of the foremost record in the magazine for displacing it from its supporting position on the latter to a like supporting position on the carrier when the same is in its raised record-receiving position, whereby upon the descent of the carrier the record is adapted to slide by gravity thereover for deposit on the turntable for play on one side and on the succeeding ascending movement of the carrier such record is moved therewith and when it reaches a predetermined position adjoining the magazine said record is tilted against the same; whereby upon the descent of the carrier the record is adapted to slide thereover to a reversed position for deposit on the turntable for play on its opposite side, and means operatively connected to said displaceable member and to said carrier for actuating them at predetermined times to their record-transferring and reversing positions and to their record-discharging position.

9. In an automatic phonograph, the combination of a turntable, a magazine at one side thereof for supporting a plurality of records side by side in a substantially upright position for transfer onto the turntable to play one or both sides thereof, loading means on said magazine and engageable with the foremost record thereon for displacing it from its magazine-supported position, a vertically-swinging carrier operable between the turntable and the magazine and normally disposed about the turntable and movable at one time to a position alongside and tilted in a direction away from the magazine, to receive the record by gravity when it is displaced from the magazine by said loading means and depositing it on the turntable during the descent of the carrier, and movable at another time to a position alongside and in tilted position toward the magazine to cause a reversal of the record by gravity during the return of the carrier to its position over the turntable, means for actuating the carrier to and from its record-transferring and record-reversing position; and means operatively connected to said loading means for rendering it operative to displace a record from the magazine onto the carrier during its initial transfer movement and for rendering such means inoperative during the record-reversing movement of the carrier.

10. In an automatic phonograph, the combination of a turntable, a record supporting magazine fixed at one side thereof from which records are adapted to be transferred onto the turntable for play, a vertically-swinging carrier operable at one time between the turntable and the magazine for transferring a record from the latter to the former by a suspended gravitating movement of the record while supported edgewise between the carrier and the magazine, said carrier being operable at another time to a reversed tilting position relative to the turntable to cause a record after play to gravitate down and be discharged therefrom, and means operatively connected to said carrier for governing its aforesaid movements.

11. In an automatic phonograph, the combina-

tion of a turntable, a record magazine at one side thereof, a vertically swinging, multi-fulcrumed carrier normally disposed about the turntable and adapted for movement about one of its fulcrums toward and from the magazine for loading the records individually from the magazine by gravitation onto the turntable and for movement about its other fulcrum relative to the turntable to a position tilted below and toward the magazine side thereof for unloading each record after play by causing it to gravitate off the carrier, means in operative relation to the magazine for displacing a record therefrom onto the carrier, and means operatively connected to said carrier for governing its fulcruming movements at predetermined times for loading a record on and unloading it from the turntable.

12. In an automatic phonograph, the combination of a turntable, a magazine at one side thereof for supporting records edgewise above the plane of the turntable, a multi-fulcrumed carrier normally disposed about the turntable for movement toward and from the magazine to load a record on the turntable for play, a combined elevating and tilting mechanism operatively connected to the carrier for moving it in sequence to an elevation in loading relation to the magazine and above the plane of the turntable, and about one of its fulcrums to an upwardly tilted position relative to the magazine to receive a record therefrom in edgewise supporting engagement between the magazine and the carrier and to a downwardly tilted position relative to and intersecting the plane of the turntable to cause the record to gravitate to a position centered over the turntable, and to its initial position below its loading relation to the magazine by a tilting of the carrier about its other fulcrum in a reverse direction relative to the turntable to deposit the record thereon for play, and means for governing said mechanism to cause the sequential movements of the carrier to its record-loading and record-depositing positions.

13. In an automatic phonograph, the combination of a turntable, a magazine at one side thereof for supporting records edgewise above the plane of the turntable, a multi-fulcrumed carrier normally disposed about the turntable for elevational and tilting movements relative thereto and to the magazine to load a record on the turntable for play and to unload a record therefrom after play, a vertically-movable member in which one of said carrier-fulcrums is located, means applied to the magazine and in operative relation with the foremost record thereon for displacing it from its edgewise-supported position to a like supported position on the carrier, and means operatively connected to said vertically-movable member and said carrier for governing the elevational and tilting movements of such parts in predetermined sequence during the record-loading cycle toward and from the magazine to receive a record therefrom and cause it to gravitate between the latter and the carrier to a playing position on the turntable and after play for governing the tilting movement of the carrier during the record-unloading cycle to and from a plane intersecting the turntable to cause the record to gravitate off the carrier to a point below the plane of the turntable.

14. In an automatic phonograph, the combination of a turntable, a record magazine at one side thereof, means for displacing the records one at a time from the magazine, and means in record-receiving relation to said displacing means for

transferring the records individually from the magazine onto the turntable and after play for unloading the records individually from the turntable, comprising a pivotally-supported carrier normally disposed about the turntable and having spaced pivots thereon located at one side of the turntable-axis at different distances therefrom, a rotating cam, and connections between the respective carrier-pivots and said cam for governing the movements of the carrier to and from its record-transferring and unloading positions.

15. In an automatic phonograph, the combination of a turntable, a record magazine at one side thereof, means for displacing the records one at a time from the magazine, and means in record-receiving relation to said displacing means for transferring the records individually from the magazine onto the turntable and after play for unloading the records individually from the turntable, comprising a pivotally-supported carrier normally disposed about the turntable and having spaced pivots thereon located at one side of the turntable-axis at different distances therefrom, pivot-engaging members depending from the carrier, a rotating cam, and operative connections between said cam and said pivot-engaging members for governing the movements of the carrier to and from its record-transferring and unloading positions.

16. In an automatic phonograph, the combination of a turntable, a record magazine at one side thereof, means for displacing the records one at a time from the magazine, and means in record-receiving relation to said displacing means for loading the records individually from the magazine onto the turntable and after play for unloading the records individually from the turntable, comprising a pivotally-supported carrier normally disposed about the turntable and having spaced pivots thereon located at one side of the turntable-axis at different distances therefrom, a vertically-guided member connected at its upper end to one of said carrier-pivots and about which pivot the carrier is adapted to swing when loading a record on the turntable and by which the carrier is shifted to a record-unloading position inclined to the turntable, a member depending from the other carrier-pivot, a rotating cam, and operative connections between said cam and said respective carrier-pivot members for governing at predetermined times the vertical displacement thereof to actuate the carrier to its loading and unloading positions.

17. In an automatic phonograph, the combination of a turntable, a magazine at one side thereof having seats for supporting a plurality of records side by side in a substantially upright position, means on said magazine and releasably engageable with the foremost record thereon for displacing its lower end from supporting engagement with the magazine-seats, and means for loading the records individually from the magazine onto the turntable and after play for unloading the records individually from the turntable, comprising a pivotally-supported carrier normally disposed about the turntable and having spaced pivots thereon located at one side of the turntable-axis at different distances therefrom, pivot-engaging members depending from the carrier, a rotating cam, operative connections between said cam and said pivot-engaging members for governing the movements of the carrier to its loading and unloading positions, and means operable in timed relation with said cam and

operatively connected to said record-displacing means to displace a record from the magazine onto the carrier at a predetermined time in the loading position of the latter.

18. In an automatic phonograph, the combination of a turntable, a record magazine at one side thereof, and a vertically-swinging carrier normally disposed about the turntable for transferring records from the magazine to the turntable and for unloading them from the latter after play, said carrier being substantially horseshoe-shaped in plan and having retaining rims at its sides and closed end for guiding the record to and arresting it at a centering position over the turntable during the swinging of the carrier from the magazine toward the turntable, and abutments applied to the open end of the carrier and against which the edge of the record is adapted to rest when such carrier is in a predetermined stage of its transferring swing, the record after play gravitating off the open end of the carrier at a predetermined time in its unloading swing.

19. In an automatic phonograph, the combination of a turntable, a record magazine at one side thereof, and a vertically-swinging carrier normally disposed about the turntable for transferring records from the magazine to the turntable and for unloading them from the latter after play, said carrier being substantially horseshoe-shaped in plan and having retaining rims at its sides and closed end for guiding the record to and arresting it at a centering position over the turntable during the swinging of the carrier from the magazine toward the turntable, abutments applied to the open end of the carrier and against which the edge of the record is adapted to rest when such carrier is in a predetermined stage of its transferring swing, the record after play gravitating off the open end of the carrier at a predetermined time in its unloading swing, and a record-engaging member disposed below the turntable and against which the bottom side of a record is adapted to contact during the unloading swing of the carrier to temporarily arrest its downward descent relative to the carrier and cause its edge to clear said carrier abutments to subsequently slide by gravity over said member and off the carrier.

20. In an automatic phonograph, a turntable, a record magazine fixed at one side thereof, a carrier movable at a predetermined time to and from a tilted unloading position relative to the turntable to lift a record from the latter and cause to gravitate down the carrier for discharge and at other predetermined times movable between the turntable and the magazine through record-loading and record-reversing cycles for transferring a record from the magazine onto the turntable for play on one side and subsequently after play movable in a like cycle to reverse the record for play on its opposite side, said magazine and carrier jointly constituting supports for the record to cause it to gravitate to its respective positions for play on one side or the other during the record-loading and record-reversing movements of the carrier, means operatively connected to said carrier for actuating it in its successive cycles between the turntable and the magazine to play one side and then the other side of the record, and means correlated with said carrier-actuating means for initiating the movement of the carrier to and from a tilted position relative to the turntable to unload a record therefrom.

21. In an automatic phonograph, a turntable,

a record magazine at one side thereof, a carrier movable at a predetermined time to and from a tilted unloading position relative to the turntable to lift a record from the latter and cause it to gravitate down the carrier for discharge and at other predetermined times movable between the turntable and the magazine through record-loading and record-reversing cycles for transferring a record from the magazine onto the turntable for play on one side and subsequently after play movable in a like cycle to reverse the record for play on its opposite side, said magazine and carrier jointly constituting supports for the record to cause it to gravitate to its respective positions for play on one side or the other during the record-loading and record-reversing movements of the carrier, means operatively connected to said carrier for actuating it in its successive cycles between the turntable and the magazine to play one side and then the other side of the record, means correlated with said carrier-actuating means for initiating the movement of the carrier to and from its tilted unloading position, and adjustable means disposed in controlling relation with said carrier-actuating means for governing the same and said correlated carrier-actuating means, said governing means being adjustable to a position to cause the carrier-actuating means to automatically operate in successive cycles to transfer and reverse the record to play both sides thereof and then render the correlated carrier-actuated means operative to tilt the carrier to an unloading position, or to a position to cause such carrier-actuating means to operate only through its transfer cycle to play the record on one side and then render the correlated carrier-actuated means operative to tilt the carrier to an unloading position.

22. In an automatic phonograph, a turntable, a record magazine at one side thereof, a carrier movable at a predetermined time to and from a tilted unloading position relative to the turntable to lift a record from the latter and cause it to gravitate down the carrier for discharge and at other predetermined times movable between the turntable and the magazine through record-loading and record-reversing cycles for transferring a record from the magazine onto the turntable for play on one side and subsequently after play movable in a like cycle to reverse the record for play on its opposite side, said magazine and carrier jointly constituting supports for the record to cause it to gravitate to its respective positions for play on one side or the other during the record-loading and record-reversing movements of the carrier, means operatively connected to said carrier for actuating it successively through its record-loading and record-reversing cycles, means correlated with said carrier-actuating means for initiating the movement of the carrier to and from its record-unloading position, and means in governing relation with said carrier-actuating means for suspending operation of the record-loading cycle of the carrier and the record-unloading cycle initiated by said correlated carrier-actuating means during the cycle of reversing the record for play on its opposite side.

23. In an automatic phonograph, a turntable, a record magazine fixed at one side thereof for supporting the records edgewise at their bottoms, a carrier movable between the turntable and the magazine for loading a record from the magazine onto the turntable for play and to a

position inclined to the turntable to unload a record therefrom after play, means applied to the magazine and engageable with the bottom edge of the foremost record therein for displacing such record from the magazine onto the carrier, means operatively connected to the carrier for actuating it to its record-loading and unloading positions, and means operatively connected to said record-displacing means and in time-governing relation with said carrier-actuating means for initiating the action of the displacing means for loading a record from the magazine onto the carrier at a predetermined time in its movement.

24. In an automatic phonograph, a turntable, a record magazine at one side thereof, a carrier movable between the turntable and the magazine for loading a record from the magazine onto the turntable for play on one or both sides and to a position inclined to the turntable to unload a record therefrom after play, means applied to the magazine for displacing a record from the magazine onto the carrier, means operatively connected to the carrier for actuating it at one time to a position for loading a record from the magazine onto the turntable for play on one side and after play to an unloading position and at another time to a position for causing a record to be reversed on the turntable to play its opposite side, means operatively connected to said record-displacing means and in time-governing relation with said carrier-actuating means for initiating the action of the displacing means for transferring a record onto the carrier at a predetermined time in the loading cycle, means for rendering the record-displacing means inoperative to load a record on the carrier during the movement of the carrier to a record-reversing position, and means in operative correlation with said carrier-actuating means for rendering the same inoperative to unload a record from the carrier during the movement of the carrier to such record-reversing position.

25. In an automatic phonograph, a turntable, a record magazine, a carrier operable relatively to such parts for loading a record onto the turntable for play and for unloading it therefrom after play, means operatively connected to said carrier for actuating it and including a rotating, double-acting cam which acts at one time to move the carrier to a record-loading position and at another time to a record-unloading position, adjustable means disposed in operative relation to said cam for governing its respective actions, and means in cooperative engagement with said cam-governing means for adjusting it to one position or the other.

26. In an automatic phonograph, a turntable, a record magazine, a carrier operable relatively to such parts for loading a record onto the turntable for play and for unloading it therefrom after play, means for displacing a record from the magazine onto the carrier, means operatively connected to said carrier for actuating it and including a rotating, double-acting cam which acts at one time to move the carrier to a record-loading position and at another time to a record-unloading position, adjustable means disposed in operative relation to said cam for governing its respective actions, a spring for normally urging said cam-governing means to a position of adjustment for rendering the carrier-actuating means operative to unload a record, and other means operatively engageable with said cam-governing means to adjust it to a position for

rendering the carrier-actuating means operative to load a record on the turntable.

27. In an automatic phonograph, a turntable, a record magazine at one side thereof, a carrier movable between the turntable and the magazine for loading a record from the magazine onto the turntable for play and to a position inclined to the turntable to unload a record therefrom after play, means applied to the magazine for displacing a record from the magazine onto the carrier, means operatively connected to said carrier for actuating it including a rotating double-acting cam which acts at one time to move the carrier to a record-loading position and at another time to a record-unloading position, gate-like means disposed in operative relation to said cam and movable to positions for governing its respective actions, means in cooperative engagement with said cam-governing gate means for initiating its movement to one position or the other, and means in operative controlling engagement with said record-displacing means for rendering such means operative only in a given position of said cam-governing gate means.

28. In an automatic phonograph, a turntable, a record magazine at one side thereof, a carrier movable between the turntable and the magazine for loading a record from the magazine onto the turntable for play and to a position inclined to the turntable to unload a record therefrom after play, means applied to the magazine for displacing a record from the magazine onto the carrier, means operatively connected to said carrier for actuating it including a rotating double-acting cam which acts at one time to move the carrier to a record-loading position and at another time to a record-unloading position, gate-like means disposed in operative relation to said cam and movable to positions for governing its respective actions, a spring for normally urging said cam-governing gate means to a position for rendering the carrier-actuating means operative to a record-unloading position, an adjustable trip means in operative governing relation to said record-displacing means and movable into and out of tripping relation with said gate means for moving the latter to a position for rendering said carrier-actuating means operative to a record-loading position and for simultaneously governing the movement of said displacing means to a position to displace a record from the magazine onto the carrier.

29. In an automatic phonograph, a turntable, a record magazine at one side thereof, a carrier movable between the turntable and the magazine for loading a record from the magazine onto the turntable for play and to a position inclined to the turntable to unload a record therefrom after play, means applied to the magazine for displacing a record from the magazine onto the carrier, means operatively connected to said carrier for actuating it including a rotating double-acting cam which acts at one time to move the carrier to a record-loading position and at another time to a record-unloading position, gate-like means disposed in operative relation to said cam and movable to positions for governing its respective actions, a trip element applied to said cam, means operatively connected to said record-displacing means for actuation by said trip element for initiating the movement of such means to a position to displace a record from the magazine onto the carrier and adjustable means disposed for movement into and out of operative relation to said cam-like gate means for initiating

its movement to a position for rendering the cam operative to move the carrier to its record-loading position, said adjustable means including a part in governing relation to said record-displacing means for rendering the latter operative to displace a record from the magazine onto the carrier.

30. In an automatic phonograph, a turntable, a record magazine at one side thereof, a carrier movable between the turntable and the magazine for loading a record from the magazine onto the turntable for play and to a position inclined to the turntable to unload a record therefrom after play, means applied to the magazine for displacing a record from the magazine onto the carrier, means operatively connected to said carrier for actuating it including a rotating double-acting cam which acts at one time to move the carrier to a record-loading position and at another time to a record-unloading position, gate-like means disposed in operative relation to said cam and movable to positions for governing its respective actions, means connected to said gate means for normally urging it to a position for rendering the carrier-actuating means operative to a record-unloading position, a trip element applied to said cam, means operatively connected to said record-displacing means for initiating its movement to a record-displacing position and including a tappet normally disposed in inoperative relation to said trip element, adjustable means disposed for alternate movement toward and from the cam and including a part movable therewith into and out of operative relation to said gate means for initiating its movement to a position for rendering the cam operative to move the carrier to its record-loading position and a part movable therewith into operative engagement with said displacing means governing tappet to bring it into tripping relation with said trip element to render the record-displacing means operative to load a record from the magazine onto the turntable, and a means on said cam and engageable with said adjustable means for governing its alternating movements.

31. In an automatic phonograph, a turntable, a record magazine at one side thereof, a carrier movable between the turntable and the magazine for loading a record from the magazine onto the turntable for play and to a position inclined to the turntable to unload a record therefrom after play, means applied to the magazine for displacing a record from the magazine onto the carrier, means operatively connected to said carrier for actuating it including a rotating double-acting cam which acts at one time to move the carrier to a record-loading position and at another time to a record-unloading position, gate-like means disposed in operative relation to said cam and movable to positions for governing its respective actions, means connected to said gate means for normally urging it to a position for rendering the carrier-actuating means operative to a record-unloading position, a trip element applied to said cam, means operatively connected to said record-displacing means for initiating its movement to a record-displacing position and including a tappet normally disposed in inoperative relation to said trip element, adjustable means disposed for alternate movement toward and from the cam and including a part movable therewith into and out of operative relation to said gate means for initiating its movement to a position for rendering the cam operative to move the carrier to its record-loading position and a part movable there-

with into operative engagement with said displacing means governing tappet to bring it into tripping relation with said trip element to render the record-displacing means operative to load a record from the magazine onto the turntable, a means on said cam and engageable with said adjustable means for governing its alternating movements, and manually-actuated means connected to that part of the adjustable means which initiates the gate means to its operative record-loading position for shifting such adjustable means and its said part to a position for rendering them inoperative.

32. In an automatic phonograph, a turntable, a record magazine, a carrier operable relatively to such parts for loading a record onto and for controlling its positioning on the turntable for playing one or both sides and for unloading a record therefrom after play, means applied to the magazine for displacing a record therefrom onto the carrier, rotatable cam means operatively connected to said carrier and said record-displacing means for actuating such parts at predetermined times to their respective record-controlling positions, and complementary trip and tappet means in governing relation to said cam means and adjustable to positions for controlling the movements of the carrier and record-displacing means to load and position the record for play on one or both sides and after play to govern the movement of the carrier to its unloading position.

33. In an automatic phonograph, a turntable, a record magazine, a carrier operable relatively to such parts for loading a record onto and for controlling its positioning on the turntable for playing one or both sides and for unloading a record therefrom after play, means applied to the magazine for displacing a record therefrom onto the carrier, a rotatable cam shaft having cam means thereon including portions operatively connected to said carrier and said displacing means for governing their movements for loading the records from the magazine onto the turntable for play on one or both sides and including a portion operatively connected to the carrier for governing its unloading movement, a switching member having a trip finger associated with said cam means for normally rendering the unloading portion thereof operative and movable to a position for rendering such portion inoperative, an adjustable trigger assembly in operative relation to said cam means including a part engageable with said trip finger for actuating the switching member to its position for rendering the loading portion of the cam means operative, and a member constituting a part of the cam-operated displacing means normally disposed in inoperative relation to its companion cam portion to render such displacing means inoperative and in correlation with said trigger assembly for actuation thereby at a predetermined time into operative relation with its cam portion to render such displacing means operative.

34. In an automatic phonograph, a turntable, a record magazine, a carrier operable relatively to such parts for loading a record onto and for controlling its positioning on the turntable for playing one or both sides and for unloading a record therefrom after play, means applied to the magazine for displacing a record therefrom onto the carrier, a rotatable camshaft having cam means thereon including portions operatively connected to said carrier and said displacing means for governing their movements for loading the records from the magazine onto the turn-

table for play on one or both sides and including a portion operatively connected to the carrier for governing its unloading movement, a switching member having a trip finger associated with said cam means for normally rendering the unloading portion thereof operative and movable to a position for rendering such portion inoperative, an adjustable trigger assembly in operative relation to said cam means, the latter including

10 a portion engageable with said trigger assembly for oscillating it toward and from a trip-governing position, said trigger assembly including a part engageable with said trip finger for actuating the switching member to its position for rendering the loading portion of the cam means operative, a member constituting a part of the cam-operated displacing means normally disposed in inoperative relation to its companion cam portion to render such displacing means inoperative and in correlation with said trigger assembly for actuation thereby at a predetermined time into operative relation with its cam portion to render such displacing means operative, and manually-controlled means operatively connected to said trigger assembly for shifting it to an inoperative position to suspend the automatic record-loading and unloading operations when it is desired to play the phonograph manually.

35. In an automatic phonograph, the combination of a turntable, a record magazine, a carrier movable relatively to such parts to transfer a record on and discharge it from the turntable, means connected to said carrier for actuating it including a driven shaft, and means for controlling the intermittent rotation of said shaft comprising a drive shaft, gearing between said shafts including a mutilated gear on said driven shaft and having a stop element thereon, a releasable stop lever disposed in the operative path of said stop element for engagement therewith to arrest said mutilated gear in a position out of driving mesh with its adjoining driven gear after a record-transferring operation, cam-like means engageable with said mutilated gear for advancing it into a drive meshing position when said stop lever is released, and means operatively connected to said stop lever for moving it to its released position to initiate the operation of the record-carrier actuating means upon the completion of play of a record.

36. In an automatic phonograph, the combination of a turntable, a record magazine, a carrier movable relatively to such parts to transfer a record on and discharge it from the turntable, means connected to said carrier for actuating it including a driven shaft, and means for controlling the intermittent rotation of said shaft comprising a drive shaft, gearing between said shafts including a mutilated gear on said driven shaft and having a stop element thereon, a releasable stop lever having a hooked end normally disposed in the operative path of said stop element for engagement therewith to arrest said mutilated gear in a position out of driving mesh with its adjoining driven gear after a record-transferring operation, a second lever in adjoining relation to said stop lever and having a cam-like portion for edgewise traversing engagement with said stop element for advancing said mutilated gear to a meshing position with its companion driven gear when the stop lever is released, an energy-storing element connected to said camming lever for urging it to a gear-advancing position, and means operatively connected to said stop lever for moving it to a re-

leased position to initiate the operation of the record-carrier actuating means upon the completion of play of a record.

37. In an automatic phonograph, the combination of a turntable, a record magazine, a carrier movable relatively to such parts to transfer a record on and discharge it from the turntable, means connected to said carrier for actuating it including a driven shaft, and means for controlling the intermittent rotation of said shaft comprising a drive shaft, gearing between said shafts including a mutilated gear on said driven shaft and having a stop element thereon, a releasable stop lever disposed in the operative path of said stop element for engagement therewith to arrest said mutilated gear in a position out of driving mesh with its adjoining driven gear after a record-transferring operation, cam-like means engageable with said mutilated gear for advancing it into a drive meshing position when said stop lever is released, an electric circuit including a solenoid and a tone-arm controlled trip switch for closing such circuit at the end of play of a record, and an operative connection between said solenoid and said stop lever for moving the latter to its released position upon the energization of the solenoid.

38. In an automatic phonograph, a turntable, a tone arm, a record magazine, a carrier movable between the turntable and the magazine for loading a record onto and for controlling its positioning on the turntable for playing one or both sides and for unloading a record therefrom after play, means for displacing a record from the magazine onto the carrier, mechanism operatively connected to said carrier for actuating it at predetermined times to its respective record-controlling positions, a manual control means in correlation with said carrier-actuating mechanism and adjustable to positions for governing said mechanism for automatic play of a record on one or both sides or for manual play, and means operatively connected to said tone arm for automatically governing its movements to and from a playing position comprising a rock shaft, means for actuating said shaft between plays of a record, a clutch mounted on said rock shaft and shiftable to and from operative engagement therewith and having an operative connection to the tone arm governing means, and an operative connection between said manual control means and said clutch for shifting the latter to a clutching position when said control means is set for playing a record on one or both sides and for shifting the clutch to a released position when said control means is set for playing a record manually.

39. In an automatic phonograph, a turntable, a tone arm, a record magazine, a carrier movable between the turntable and the magazine for loading a record onto and for controlling its positioning on the turntable for playing one or both sides and for unloading a record therefrom after play, means for displacing a record from the magazine onto the carrier, mechanism operatively connected to said carrier for actuating it at predetermined times to its respective record-controlling positions, means for initiating the starting and stopping of said carrier-actuating mechanism at predetermined times including an electrically-governed control device, a circuit including a switch and said control device for rendering the latter operative to start the carrier-actuating means, means operatively connected to said tone arm for automatically governing its movements to and from a playing position, and a

5 manual control means in correlation with said carrier-actuating mechanism and said tone arm moving means and adjustable to positions for governing such mechanism and means simultaneously operative for automatic play of a record on one or both sides or for manual play, said manual control means including a part in governing relation with said electrically-governed control device switch for closing the same when the control means is adjusted to a position for playing a record on one or both sides and for opening said switch when the control means is set to a position for playing a record manually.

10 40. In an automatic phonograph, a turntable, a tone arm, a record magazine, a carrier movable between the turntable and the magazine for loading a record onto and for controlling its positioning on the turntable for playing one or both sides and for unloading a record therefrom after play, means for displacing a record from the magazine onto the carrier, mechanism operatively connected to said carrier for actuating it at predetermined times to its respective record-controlling positions, means for initiating the starting and stopping of said carrier-actuating mechanism at predetermined times including an electrically-governed control device, a circuit including a switch and said control device for rendering the latter operative to start the carrier-actuating means, means operatively connected to said tone arm for automatically governing its movements to and from a playing position, a manual control means in correlation with said carrier-actuating mechanism and said tone arm 15 moving means and adjustable to positions for governing such mechanism and means simultaneously operative for automatic play of a record on one or both sides or for manual play, said manual control means including a part in governing relation with said electrically-governed control device switch for closing the same when the control means is adjusted to a position for playing a record on one or both sides and for opening said switch when the control means is set to a position for playing a record manually, 20 25 30 35 40 45 50 55 60 65 70 75

an electric motor for transmitting motion to said carrier-actuating mechanism and to said tone arm moving means, a magnetic switch in the circuit of said motor adapted to be manually opened and closed and magnetically opened, and a second switch included in the motor-switch circuit for governing the same to automatically open said motor-switch, said second switch being disposed in operative correlation with said manual control means to remain open when such means is set for automatic playing of the records on one or both sides and to be closed to open the motor circuit when the control means is set for playing a record manually.

41. In an automatic phonograph, a turntable, a tone arm, a record magazine, means for transferring records one at a time from the magazine onto the turntable for play and after play for discharging them therefrom, means operatively connected to the tone arm for moving it to and from its play position, an electric motor for transmitting motion to said record-transferring and tone arm positioning means, a magnetic switch in the circuit of said motor adapted to be manually opened and closed and magnetically opened, a start and stop mechanism for said record-transferring means including an electrically-governed control device, a tone arm trip switch, a circuit including said trip switch and said control device, and a manually-governed multiple

switch having one terminal thereof included in the circuit of the motor-switch and the other terminal thereof included in the circuit of said start and stop mechanism control device, whereby in the closed position of one of the multiple switch terminals its controlling circuit is closed and the other is opened and vice versa, whereby to render the start and stop mechanism operative during the continuous automatic playing of the records and inoperative during the manual play of the records.

42. In an automatic phonograph, a turntable, a magazine fixed at one side thereof for supporting records edgewise thereon in a position inclined to the vertical and sloping downwardly toward and relatively to the turntable, record-transferring and positioning means normally disposed about the turntable and movable toward and from the magazine to assume traversing positions inclined to either side of the vertical to either receive a record from the magazine or reverse its position on the carrier and gravitate it between the magazine and the carrier for presentation onto the turntable for playing it on one side or the other, and means in operative relation to the magazine for displacing a record therefrom onto the record transferring means, and means operatively connected to said record-transferring means for governing its movements to and from either of its inclined positions.

43. In an automatic phonograph, a turntable, a magazine fixed at one side thereof for supporting records edgewise thereon in a position inclined to the vertical and sloping downwardly toward and relatively to the turntable, and a tiltable carrier movable between the turntable and the magazine to and from a given position inclined in opposing loading relation to the magazine to receive a record therefrom and deposit it on the turntable for play on one side and to and from a position relative to and inclined in the same general direction as the magazine to tilt such record toward the magazine to cause its position to be reversed when the carrier is returned to a position to redeposit the record on the turntable for play on its opposite side, the record during its initial transfer and subsequent reversal gravitating between the magazine and the carrier during the lowering of the latter toward the turntable.

44. In an automatic phonographic, the combination of a turntable, a record magazine, mechanism for transferring a record from the magazine onto the turntable, means for actuating said mechanism including a driven shaft, and means for controlling the intermittent rotation of said shaft comprising a continuously rotating drive shaft, gearing between said shafts including a mutilated gear on said driven shaft having a retractile tooth at one end of its mutilated portion and a stop element projecting from one face thereof, a releasable stop lever disposed in the operative path of said stop element for engagement therewith to arrest said mutilated gear in a position out of driving mesh with its adjoining driven gear after a record-transferring operation, a power-transmitting member engageable with said mutilated gear for advancing it into a drive-meshing position when said stop lever is released, and means operatively connected to said stop lever for moving it to a released position to initiate the operation of said record-transferring mechanism upon the completion of play of a record.

OTTO A. HOKANSON.
